UNITED STATES PATENT OFFICE.

RALPH P. THOMPSON AND EMIL KOEB, OF SPRINGFIELD, OHIO.

GAS-ENGINE.

SPECIFICATION forming part of Letters Patent No. 729,700, dated June 2, 1903.

Application filed November 8, 1901. Serial No. 81,642. (No model.)

To all whom it may concern:

Be it known that we, RALPH P. THOMPSON and EMIL KOEB, citizens of the United States, residing at Springfield, in the county of Clark 5 and State of Ohio, have invented a certain new and useful Improvement in Gas-Engines, of which the following is a specification.

This invention relates especially to supplying air under pressure to the compression and explosion chamber for clearance of the chamber of the products of an exploded charge and furnish fresh air for the next-to-be-exploded charge, and has for its object to supply a regulated quantity of air proportionate 15 to the amount needed and no more for each operation, to insure a clearance of the compression and explosion chamber of the exploded gases and vapors before the introduction of the fresh-air supply and a new charge 20 to the chamber, to furnish a clear passage between the air-chamber and the compression and explosion chamber of the engine and the exhaust by which the initial pressure from the pump will force the air therefrom through 25 the compression and explosion chamber and down the eduction-port to clear such chamber of the previously-exploded charge, to operate the power-pistons and the air-pump piston in the same axial line with the air-pump 30 piston connected to and operated from one of the power-pistons and having an increased diameter over the diameter of the power-pistons, to utilize only so much of the full stroke of the air-pump piston as is required to supply 35 the air needed to clear the compression and explosion chamber of the previously-exploded charge and furnish fresh air for the next charge, to control the air for the blast supplied from the pump by providing escape- 40 passages in the cylinder of the pump for a portion of the stroke of the piston, leaving only a chamber of the requisite capacity for the amount of air to be supplied to the explosion-chamber, to prevent excessive pressure 45 in the air-pump cylinder and insure a compression of the air-supply for the charge previous to the explosion within the explosion-chamber, to improve the construction and operation of the air-supply pump and its 50 piston and cylinder and its operation with the explosion-chamber and the power-pistons, and to improve generally the construction

and operation of the parts pertaining to the operation of the power-pistons and the pump-piston and the general relation of the parts 55 as a whole one to the other; and the invention consists in the features of construction and the combinations of parts hereinafter described and claimed.

In the drawings, Figure 1 is a top or plan 60 view of a gas-engine, showing the cylinder for the explosion-chamber and the power-pistons and the cylinder for the air-pump piston and also the cross-heads, connecting-rods, cranks, and crank-shaft; Fig. 2, a vertical central longitudinal section through the cylinder and pistons, showing the power-pistons receded and in position for an explosion of the charge and showing the air-pump piston receded; Fig. 3, a similar view to Fig. 2, 70 showing the power-pistons advanced nearly to the limit of their stroke and the pump-piston advanced to a point where it will act and force air into the explosion-chamber, with the eduction-port for the exploded charge 75 slightly opened and the induction-port for the fresh air just ready to open; and Fig. 4, a similar view to Fig. 2, showing the power-pistons advanced to the limit of their stroke and the air-pump piston advanced to the 80 limit of its stroke and with the induction and eduction ports for the explosion-chamber both open, leaving a clear passage through the explosion-chamber for the air forced thereinto by the advance of the pump-piston. 85

In the drawings only so much of a complete engine is illustrated as is deemed necessary to show the construction, relation, and operation of the parts pertaining to the invention, which relates to the air-pump and the explosion-chamber and the parts coöperating therewith.

The main or engine cylinder proper, A, has at one end a neck or short extension A' and at the opposite end an extension A², and the combined length of the cylinder and its extensions is to be such as to furnish the chamber for the travel of the pistons and a support for the pistons. At the center, longitudinally of the main cylinder, on one side 100 thereof, is an opening a, furnishing admission to the explosion-chamber of the cylinder, and through which the gas and air for the charge are admitted to the explosion-chamber

from a suitable charging appliance. (Not shown, as it forms no part of the present invention.) The cylinder A on each side of the opening a has a double wall, furnishing an annular passage a' around the cylinder on each side of the charging-opening, and, as shown, communication is established between the two passages by ports a^2 and a suitable connecting-pipe, (not shown,) and an education-port a^3 is provided for carrying off the cooling medium from the passages. At each end of the main cylinder in the arrangement shown is a port a^4 for supplying oil or other lubricant to the power-pistons, which operate in the main cylinder at each end thereof. The interior of the main cylinder forms as a whole a single explosion-chamber, with end chambers for the travel of the power-pistons, and the piston-chambers B and B' are separated for a portion of the diameter of the cylinder by an arched wall or bridge B², located in line with the charging openings or passage a , and at one side of the wall or bridge is an induction port or opening b for supplying fresh air to the explosion-chamber, and at the opposite side of the arched wall or bridge is an education port or passage b' for escaping the burned gases and vapors after each explosion, and between the inner end of the arched wall or bridge and the charging opening or passage a is an opening b^2 , so that the explosive charge can lie between the two operating or power pistons, making the explosion-chamber common to both pistons.

The chamber B has located and operating therein a power-piston C, and the chamber B' has located and operating therein a power-piston C', which pistons have a reciprocating travel in their respective chambers to the limit of their strokes. Each power-piston in the construction shown consists of a cylindrical wall or shell c , a closed end wall c' , and suitable packing-rings c^2 , extending circumferentially around the piston at the inner end thereof. The body of the piston C is longer than the body of the piston C' and at its outer or advanced end carries a piston D, which may be cast or formed with the piston C or be separate therefrom and suitably connected therewith. The piston D is of a greater diameter than the piston C, with which it is connected, and is formed of a circumferential rim or shell d and an end wall d' , with circumferential packing-rings d^2 in the rim or shell of the outside. This piston is located and operates in a chamber E within a cylinder or casing F, which may be formed with the neck or end extension A' of the cylinder A or may be separate therefrom and suitably attached thereto. The open end or the cylinder or shell F in the arrangement shown is closed by a cap or cover F', having therein perforations or holes f , which are closed by a flap-valve e , attached to the inner face of the cap and having its free end overlying the perforations or holes, so as to effectually close the perforations or holes when the valve is

down, and when the valve is raised open the perforations or holes for the admission of air into the chamber E in advance of the piston therein. The cap or head F' has therein a port or passage g , which communicates with a pipe or conduit G, leading to the induction-port b of the explosion-chamber, so that with the advance or outward stroke of the piston C, carrying with it the piston D, air will be forced from the chamber E through the port or opening g , pipe or conduit G, and port or opening b into the compression and explosion chamber, when the piston C is advanced a sufficient distance to uncover the induction port or opening leading into the compression and explosion chamber. The shell or casing F forms the cylinder of an air-pump, having therein the chamber E, in which the air-pump piston D operates. The chamber E and the pump-piston therein are of an increased diameter over the chamber B and the power-piston C therein, giving the air-pump an increased capacity over the capacity of the compression and explosion chamber, which, if the piston of the pump was operative its full stroke, would furnish a greater supply of air than required for use in clearing the explosion-chamber and furnishing the fresh air for the next charge. It is essential and necessary that the amount of fresh air supplied to the compression and explosion chamber must be sufficient to clear such chamber of the gases, vapors, and products arising from an exploded charge and at the same time not have the supply of fresh air in excess of what is actually needed for clearance and for the new charge of air. The regulation and control of the fresh supply of air from the air-pump is wholly by means of the piston of the pump and its containing-cylinder and is obtained by utilizing only a sufficient length of the stroke of the air-pump piston as is needed for the supply, allowing the piston to operate during a portion of its stroke without forcing air from the chamber to enter the compression and explosion chamber. The arrangement for regulating and controlling the air-supply shown is carried out by forming openings or passages in the shell or wall of the air-pump cylinder, which openings or passages terminate at a predetermined point forward, where a sufficient-length stroke remains to furnish the supply of air necessary for clearance and charging purposes in the compression and explosion chamber.

The power-piston C is carried by a cross-head H, and the power-piston C' is carried by a cross-head H'. The cross-head H at each end has connected thereto a crank-rod I, which operates a crank J of a crank-shaft K, and the cross-head H' at each end thereof has connected thereto a crank-rod I', which operates a crank J' on the crank-shaft, and the cranks J and J' project on opposite sides of the crank-shaft, as usual. The crank-shaft passes under the arch or wall B² and is supported by an arm or standard L, extending up from

a base-plate L' , bolted or otherwise secured to the cylinder A , and the base-plate L' in turn is supported on angle-beams M , forming a portion of a suitable framework for the engine. (Not shown.)

The cross-head H extends both sides of the power-piston C , which it carries, passing through elongated openings h therefor formed in the wall or shell of the neck A' and air-pump cylinder F , and the cross-head H' also extends on both sides of the cylinder C' , which it carries, passing through an elongated opening therefor formed on opposite sides of the shell or wall of the end extensions A^2 of the main or engine cylinder, and, as shown, the openings h and h' are of an elongated diamond shape, with the inner end of each opening terminating in the end of the main or engine cylinder. The opening H at its outer or advanced end extends into the body or wall of the shell or cylinder F , and these openings h furnish the escape-passages for the air from the pump-cylinder in advance of the piston thereof to force air from the chamber of the cylinder through the conduit into the compression and explosion chamber of the engine. The terminus of the outer or advance end of each opening h is at a line to leave a chamber between the ends of the opening and the cap or head F' , which chamber between the piston and the head or cap after the piston passes the end of the opening is of a capacity to furnish the required amount of air for clearance and supplying air to the compression and explosion chamber with but little, if any, excess of supplied air over what is wanted for operation in the compression and explosion chamber.

The operation is as follows: The engine when in condition for operation to receive a charge in the compression and explosion chamber for explosion therein to drive outward or advance the power-pistons has the several elements which enter into the present invention in the position shown in Fig. 2, in which position the power-pistons are both at the limit of their inward or return stroke, with their closed ends adjacent to the opposite sides of the arch or wall B^2 and with the piston D of the force-pump for the air in initial or receded position, as shown in Fig. 2. The space between the power-pistons when in the position shown in Fig. 2 forms a contracted compression and explosion chamber, in which the explosion will act against the closed end walls of the power-pistons to force such pistons outward or in the direction of their advance stroke, and the space between the receded pump-piston and the head or cap F' forms an air-chamber which has a free communication through the openings h in advance of the piston with the outside of the cylinder F , so that with the initial outward movement or advance of the air-pump piston air will escape through the openings until the openings are covered by the rim or flange of the piston. The explosion of the gas in

the compression and explosion chamber of the main or engine cylinder forces the power-pistons outward or in the direction of the advance stroke, the force of the explosion passing on both sides of the arch or wall, which serves as a deflector, insuring an equal effect practically on both power-pistons from the explosion, and the force of the explosion will continue to act with its full effect until the piston C' at its closed end passes the port or opening b' , allowing the gases and vapors of the explosion to flow out at the opened port or passage and escape from the single explosion-chamber, and as the piston C' reaches and passes the inner edge of the port or passage b' the piston C has reached a point where the induction port or passage will be opened with the further outward movement or advance of the piston C and the pump-piston D has reached a point where its wall or rim closes the escape or discharge passages from the chamber E , confining the air in the chamber between the piston and the head F' , as shown in Fig. 3, in which position the products of the explosion can escape from the compression and explosion chamber at the eduction port or passage b' , partially clearing the chamber of the products of the explosion before the induction port or passage b is opened for the admission of fresh air into the compression and explosion chamber. The completion of the outward movement or advance stroke of the power-pistons brings the pistons into the position shown in Fig. 4, in which position the induction port or passage and the eduction port or passage are both open to their full extent for the free inflow and outflow of the fresh air forced into the compression and explosion chamber by the advance stroke or outward movement of the air-piston, which with the parts as in Fig. 4 has completed its stroke. The amount of air in the chamber E with the piston D in the position shown in Fig. 3 is sufficient for the purpose of effectually clearing the compression and explosion chamber, as such air is forced from the chamber E through the conduit G into the compression and explosion chamber, so that with the completion of the outward movement or advance stroke of the air-pump piston the compression and explosion chamber will be free from the burned products of the previous explosion, with the result that the next charge will be pure fresh air uncontaminated with any of the gases or vapors and products of the previous explosion.

The induction and eduction ports or passages of the compression and explosion chamber are open for clearance from the time the power-pistons reach and pass the position shown in Fig. 3 until the pistons reach the position shown in Fig. 4, and during this period of time the advance of the pump-piston continues forcing air from chamber E through the conduit for the air to pass through the compression and explosion chamber, and

the ports or passages of the compression and explosion chamber will remain open during the inward movement or return stroke of the piston until the power-pistons reach 5 and pass from the position inward, (shown in Fig. 3,) and during such inward movement or return stroke the air forced into the chamber will be discharged therefrom through the eduction port or passage until such port or 10 passage is closed by the piston C', and for the remainder of the rearward movement or return stroke of the power-piston the air in the compression and explosion chamber will be compressed between the two power-pistons 15 until such pistons reach the position shown in Fig. 2, at which time another charge is entered and exploded in the chamber, forcing the pistons forward to the limit of the advance stroke, as already described, during 20 which movement the pistons of the engine and the pump-piston will operate, as described, to open the ports or passages and force a blast of air from the chamber of the air-pump through the compression and explosion chamber 25 for clearance purposes, and this operation will continue as long as it is desired to run or operate the engine.

The compression and explosion chamber is, in effect, a single chamber; but by reason of 30 the arch or wall at the center thereof its ends become chambers, one for each power-piston, in which the pistons are reciprocated from the cross-heads and the connecting-rods from the cross-heads to the cranks of the crank- 35 shaft, as usual in the operation of a two-cylinder gas-engine. The interior diameter of the pump-cylinder and of the piston operating therein is greater than the interior diameter of the engine-cylinder and the power- 40 pistons operating in such cylinder, and as a result the chamber of the pump can have escape-passages which permit of a free advance or forward movement of the pump-piston for a length of stroke sufficient to create the blast 45 of air required without any back pressure, as the air in the chamber in front of the piston is free to pass out through the escape-openings without producing a resistance sufficient to interfere with the advance of the 50 pump-piston until the limit of the escape-opening is reached, and by having the eduction-port of the engine-cylinder open prior to the opening of the induction-port a free escape for the product of the explosion is pro- 55 vided, which leaves the cylinder for the power-pistons free of back pressure which might interfere with the inward movement or return stroke of the piston. It will thus be seen that in operation both the pump and the engine- 60 cylinders are free of back pressure to an injurious extent on the inward movement or return stroke of the power-pistons to normal position, which is desirable in the operation of gas-engines, and it will also be seen that by 65 means of the force-pump for the air a blast of air is carried through the compression and explosion chamber, so as to produce a perfect

clearance in such chamber for the next charge to be pure fresh air uncontaminated with the gases, vapors, and products of a previous ex- 70 plosion.

What we claim as new, and desire to secure by Letters Patent, is—

1. In a gas-engine, and in combination with the compression and explosion chamber there- 75 of, an air forcing and supply pump, having an air-escape in the wall of its cylinder at a predetermined distance forward or in advance of the limit of the inward movement or return stroke of its piston, said air-escape opened 80 and closed by the movements of the pump-piston and when opened furnishing a free es- cape and clearance of air in front of the pis- ton and preventing back pressure on the pis- ton, and when closed forming an air-chamber 85 in advance of and closed at one end by the piston, the chamber having communication with the compression and explosion chamber and having a capacity for a sufficiency of air to clear the compression and explosion cham- 90 ber of the engine of a previously-exploded charge and to furnish the air for the next suc- ceeding explosive charge, substantially as de- scribed.

2. In a gas-engine, and in combination with 95 the compression and explosion chamber there- of, an air forcing and supply pump having a cylinder of an interior diameter greater than the interior diameter of the explosion-cham- 100 ber of the engine and having an escape-open- ing in its wall at a predetermined distance forward or in advance of the limit of the in- ward movement or return stroke of its pis- ton, said escape opened and closed by the 105 movements of the pump-piston, and when opened furnishing a free escape and clear- 110 ance of air in front of the piston and pre- venting back pressure on the piston, and when closed forming an air-chamber in advance of and closed at one end by the pump-pis- 115 ton, the chamber having communication with the compression and explosion chamber and having a capacity for a sufficiency of air to clear the compression and explosion cham- 120 ber of the engine of the previously-exploded charge and to furnish the air for the next suc- ceeding explosive charge, substantially as de- scribed.

3. In a gas-engine, the combination of an engine-cylinder having therein a compression and explosion chamber, a power-piston located and operating in the engine-cylinder in jux- 125 tarelation to the explosion-chamber, an air forcing and supply pump having its cylinder in axial line with and of greater interior di- 130 ameter than the power-cylinder and provided through its wall with an escape opening or passage for air, located at a predetermined point in relation to the traverse of the pump- 135 piston, a pump-piston located and operating in the air-pump cylinder for its movements to open and close the escape opening or pas- sage, and when opened furnishing a free es- cape and clearance of air in front of the pis-

ton and preventing back pressure on the piston, and when closed forming an air-chamber in advance of and closed at one end by the pump-piston, and a conduit leading from the 5 chamber of the air-pump forward of the piston to the compression and explosion chamber in the engine, for conveying air from the chamber of the pump to the compression and explosion chamber, substantially as described.

4. In a gas-engine, the combination of an engine-cylinder provided with a compression and explosion chamber, an arch or wall projecting into the compression and explosion 15 chamber of the engine-cylinder, a pair of power-pistons on opposite sides of the arch or wall, an air forcing and supply pump having its cylinder in axial line with and of greater interior diameter than the power-cylinder 20 and provided through its wall with an escape opening or passage for air located at a predetermined point in relation to the traverse of the pump-piston, a pump-piston located and operating in the air-pump cylinder 25 for its movements to open and close the escape opening or passage, and when opened furnishing a free escape and clearance of air in front of the piston and preventing back pressure on the piston and when closed forming 30 an air-chamber in advance of and closed at one end by the pump-piston, and a conduit leading from the chamber of the air-pump forward of the piston to the compression and explosion chamber in the engine, for conveying 35 air from the chamber of the pump to the compression and explosion chamber, substantially as described.

5. In a gas-engine, the combination of an engine-cylinder having therein a compression 40 and explosion chamber, a power-piston located and operating in the engine-cylinder in juxtaposition to the explosion-chamber, an air forcing and supply pump having its cylinder in axial line with and of greater interior diameter than the power-cylinder and provided through its wall with an escape opening or 45 passage for air, located at a predetermined point in relation to the traverse of the pump-piston, a pump-piston located and operating in the air-pump cylinder for its movements to open and close the escape opening or passage and when opened furnishing a free escape and 50 clearance of air in front of the piston and preventing back pressure on the piston and when 55 closed forming an air-chamber in advance of and closed at one end by the pump-piston, an eduction-port at the front or outer end of the chamber of the air-pump and a conduit connecting the eduction-port of the air-pump 60 with the induction-port of the compression and explosion chamber of the engine, for conveying air from the chamber of the pump to the compression and explosion chamber, substantially as described.

6. In a gas-engine, the combination of an engine-cylinder having a compression and explosion chamber, a pair of power-pistons op-

erating in the engine-cylinder on opposite sides of the compression and explosion chamber, an eduction and induction port or passage for the compression and explosion chamber, each port or passage opened and closed by the traverse of the power-piston, an air forcing and supply pump having its cylinder in axial line with and of a greater interior diameter than the engine-cylinder and provided through its wall with an escape opening or passage for air, located at a predetermined point in relation to the movements or strokes of the air-pump piston, a piston located and operating in the air-pump cylinder controlling the opening and closing of the air-escape, and when opened have the air-escape and furnish a clearance of air in front of the piston and preventing back pressure on the piston, and when closed forming an air-chamber in advance of and closed at one end by the pump-piston, an eduction-port at the front or outer end of the air-chamber of the air-pump, and a conduit connecting the eduction-port of the air-pump with the induction-port of the compression and explosion chamber of the engine, for conveying air from the chamber of the pump to the compression and explosion chamber, substantially as described.

7. In a gas-engine, the combination of an engine-cylinder having a compression and explosion chamber, an arch or wall projecting into the compression and explosion chamber, a pair of power-pistons operating in the engine-cylinder on opposite sides of the arch or wall, an eduction-port on one side of the arch or wall, an induction-port on the opposite side of the arch or wall, said ports controlled by the traverse of the respective power-pistons in the engine-cylinder, for the eduction-port to open before the induction-port is opened, allowing escape of the products of the explosion before the pistons reach the limit of their outward or advance stroke, and an air-pump having its cylinder provided with an escape through its wall for preventing back pressure on the pump-piston and having the escape closed at the advance of the piston at a predetermined line forming an air-chamber in advance of the piston, said air-chamber having communication with the induction-port of the engine-cylinder, substantially as described.

8. In a gas-engine, the combination of an engine-cylinder having a compression and explosion chamber, an arch or wall projecting into the compression and explosion chamber, a pair of power-pistons operating in the engine-cylinder on opposite sides of the arch or wall, an eduction-port on one side of the arch or wall, an induction-port on the opposite side of the arch or wall, said ports controlled by the traverse of the respective power-pistons in the engine-cylinder for the eduction-port to open before the induction-port is opened, allowing the escape of the products of the explosion before the pistons reach the limit of their outward or advance stroke, and an air-pump

having its cylinder provided with an escape through its wall for preventing back pressure on the pump-piston and having the escape closed at the advance of the pistons at a predetermined line, forming an air-chamber in advance of the piston, a port at the front end of the air-chamber, and a conduit leading from the port to the induction-port of the compression and explosion chamber for supplying air from the pump-chamber to the compression and explosion chamber, substantially as described.

9. In a gas-engine, the combination of an engine-cylinder having a compression and explosion chamber, a pair of power-pistons located and operating in the engine-cylinder, an induction and an eduction port for the compression and explosion chamber opened and closed by the traverse of the power-pistons, for the eduction-port to remain open with the induction-port opened, and to close before the induction-port is closed, and an air forcing and supply pump located in axial line with the cylinder, and having the wall of the pump-cylinder provided with an air-escape at a predetermined distance for-

ward or in advance of the limit of the inward movement or return stroke of the piston of the air-pump, said air-escape opened and closed by the movement of the pump-piston 30 and when opened furnishing a free escape and clearance of air in front of the piston and preventing back pressure on the piston, and when closed forming an air-chamber in advance of and closed at one end by the pump-piston, the chamber having communication with the induction-port of the compression and explosion chamber for initially supplying air to the chamber for the clearance of the chamber from the products of the previously-exploded charge and continuing the supply of air with the eduction-port of the compression and explosion chamber closed to furnish the air for the next succeeding explosive charge in the compression and explosion chamber, substantially as described. 35 40 45
